Patented Dec. 30, 1913.

UNITED STATES PATENT OFFICE.

JAMES S. KNOWLSON, OF LA GRANGE, ILLINOIS, ASSIGNOR TO ELECTRO-MAGNETIC TOOL COMPANY, OF CHICAGO, ILLINOIS, A CORPORATION OF ILLINOIS.

MECHANICAL HAMMER.

1,082,880.

Specification of Letters Patent.

Patented Dec. 30, 1913.

Application filed February 15, 1913. Serial No. 748,547.

To all whom it may concern:

Be it known that I, JAMES S. KNOWLSON, a citizen of the United States, residing at La Grange, in the county of Cook and State 5 of Illinois, have invented a new and useful Improvement in Mechanical Hammers, of which the following is a specification.

My invention relates, more particularly, to mechanical hammers for delivering blows 10 against a reciprocable tool, as for example, a rock, stone or cement drill, and especially to the type of hammers involving, generally stated, a rotary member equipped with pivoted hammers which swing outwardly under 15 centrifugal force to a position where they will deliver blows to the tool, and rebound, after striking the tool, to a position in which they will clear the tool.

My objects, generally stated, are to provide a hammer of the type above referred to which will operate to deliver sharp clean blows against the tool, and may be operated at relatively high speed without drag, or rebound, against the tool.

A further object is to reduce wear of the moving parts to the minimum; and to so arrange the hammers that the blows produced thereby, when rebounding against the rotary member to which they are pivoted, will tend to accelerate said rotary member rather than decelerate it.

Referring to the accompanying drawing Figure 1 is a view in elevation of a hand-hammer constructed in accordance with my invention. Fig. 2 is a section taken at the line 2 on Fig. 1 and viewed in the direction of the arrow, this view showing by full lines the pivoted hammers in the positions they assume when the mechanism is at rest, the dotted circle indicating the path through which the outer edges of the pivoted hammers travel when swung outwardly on their rotary support by the action of centrifugal force. Fig. 3 is a view taken at the line 3 on Fig. 2 and viewed in the direction of the arrow; and Fig. 4, a perspective view of one of the two similar hammers employed.

The casing for the hammer mechanism is illustrated at 5 and is formed at its upper end with a hand-grip 6, and at its lower end with a sleeve-section 7 containing a bearing-member 8, the aperture 9 therethrough, pref-

erably being of angular shape in cross-section, this bearing serving to receive and guidedly confine a tool such as that represented at 10, the latter being provided with a section 11, corresponding in cross section with the shape of the opening 9 and slideable therein, and a shouldered section 12 against which the casing 5 is adapted to bear in the 55 operation of the mechanism, the shoulder 12 being so disposed that it will cause the upper end of the tool 10 to extend into a position, in the interior of the casing 5, wherein it will receive the blows delivered by the hammers, 60 65 hereinafter described.

Journalized in bearings 13 on the casing 5 is a shaft 14, provided with an operating-handle 15 and carrying a gear 16 which meshes with a pinion 17 fixed on a shaft 18 70 journalized in bearings 19 in the casing. The shaft 18 has rigidly secured thereto a bar 20 which extends at right angles to said shaft and preferably equidistantly beyond the opposite sides thereof. The bar 20, 75 which is adapted to be rapidly rotated by turning the crank 15, forms the support for hammers 21, which are pivoted as indicated at 22 to this bar toward the opposite ends of the latter. In the construction illustrated 80 at 23, the hammers 21 are recessed as indicated at 23, thereby affording spaced sections 24 at which the hammers straddle bosses 25 provided on the bar 20 and extending in opposite directions thereon, the pivot-pins 22 85 passing through the sections 24 and the bosses 25. The bosses 25 are preferably so disposed as to cause the pins 22 to be diametrically opposed about the shaft 18 as represented in Fig. 2, and disposed at opposite sides of said bosses are stop-surfaces 26 and 27, with which the surfaces 28 and 29 of the hammers 21 are adapted respectively to coöperate for holding the hammers in striking position and serving as steps therefor upon rebound of the hammers, respectively, the opposite ends of the bar 20 adjacent to its stop-surfaces 26 being bifurcated as represented at 30.

The various parts of the mechanism described are so arranged, as illustrated, as to cause the hammer 21, when swung outwardly to the full line position represented of the lowermost hammer in Fig. 2 and the

dotted position represented of the hammer in the upper part of this figure, to be in position for striking against the upper end of the tool 11 while traversing the path represented by the dotted circle α , the ends of the bar 20, as the latter is rotated, passing at their bifurcated portions 30 over the upper end of the drill 10. The hammers 21, upon striking the drill 10, are swung backward, by force of the impact, and toward the axis of rotation of the bar 20, into engagement at their surfaces 29 with the stop-surfaces 27 and into engagement with bosses 31 provided on the bars 20.

It is highly desirable in a mechanism of this character that clean sharp blows be delivered by the hammers against the tool and that rebound of the hammers against the drill be prevented. To these ends I so dispose the stop-surfaces 26 and the pins 22 as to cause the centers of gravity of the hammers to be in the rear of the pivots 22, whereby centrifugal force will cause the hammers 21, in returning to striking position, after delivering a blow against the drill, to be held against the stop-surfaces 26 which are so disposed as illustrated as to cause the blow delivered by the hammers to be tangential to a circle described about the axis of the shaft 22; and so dispense the stop-surfaces 26 on the bar 20 as to cause the hammers 22 to swing through a relatively great arc in opposition to centrifugal force, after striking the drill, whereby centrifugal force is utilized to cushion in a measure the force of the hammer in swinging backwardly as stated, which serves to reduce the blow of the hammer against the coöperating stop-surface 27, thus minimizing jarring of the moving parts of the mechanism. With a view to further reducing the jarring of the parts of the mechanism and the subjection of the latter to shocks, I dispose the stop-surfaces 27 between the pivots 22 and the shaft 18, and forwardly offset these stop-surfaces as represented in Fig. 2. Thus, by locating the stop-surfaces between the pivots 22 and the shaft 18, the blows produced by the hammers 21 against the bar 20, when the hammers swing back after striking the drill, tend to accelerate rather than decelerate the rotation of the bar 20; and by positioning the stop-surfaces 27 in advance of the pivots 22, the hammers upon rebounding from the tool and against the bar 20 are caused to travel through an arc of relatively large degree before striking the stop-surfaces with the advantage hereinbefore pointed out.

While I have illustrated and described a particular construction of hammer-mechanism embodying my invention, I do not wish to be understood as intending to limit it to such construction as the same may be vari-

ously modified and altered without departing from the spirit of my invention.

What I claim as new and desire to secure by Letters Patent is—

1. In a device of the character set forth, the combination of a rotary member and a hammer pivoted thereto and adapted to be moved into striking position by centrifugal force, the pivot of said hammer being so located relative to the axis about which said rotary member turns, as to cause said hammer on recoiling to strike against said rotary member wholly intermediate the axis of rotation of the latter and the pivot of said hammer. 75

2. In a device of the character set forth, the combination of a rotary member, and hammers pivoted thereto in balanced condition about the axis of said rotary member and adapted to be moved into striking position by centrifugal force, the pivots of said hammers being so located relative to the axis about which said rotary member turns, as to cause said rotary hammers on recoiling to strike against said rotary member wholly intermediate the axis of rotation of the latter and the respective pivots of said hammers. 85

3. In a device of the character set forth, the combination of a rotary member, and a hammer pivoted thereon and adapted to be moved into striking position by centrifugal force, said rotary member being provided with a stop-surface for said hammer during recoil located wholly between the axis upon which said hammer turns and the axis of said rotary member and in advance of the axis of said hammer, whereby said hammer in recoiling strikes said rotary member wholly between the axis upon which the hammer turns and the axis of the rotary member, for the purpose set forth. 95

4. In a device of the character set forth, the combination of a one-piece rotary member, provided with bosses at its opposite ends and flanked by inner and outer stop-surfaces, and hammers pivoted on said bosses and adapted to be moved into striking position by centrifugal force and bear against said outer stop-surfaces, the pivots of said hammers being so located relative to the axis of said rotary member as to cause said hammers on recoiling to strike said inner stop-surfaces on said rotary member, thus delivering the recoil-blow of the hammer against said rotary member intermediate the axis of rotation of the latter and the pivot of the hammer. 115

JAMES S. KNOWLSON.
